(57) **CLAIM**

The ornamental design for a golf tool, as shown and described.

DESCRIPTION

FIG. 1 is a perspective view of a golf tool showing my new design with the divot repair element of the tool fully retracted;

FIG. 2 is a top plan view thereof;

FIG. 3 is a bottom plan view thereof;

FIG. 4 is an elevation view of the front side thereof;

FIG. 5 is an elevation view of the back side thereof;

FIG. 6 is an elevation view of the left end thereof;

FIG. 7 is an elevation view of the right end thereof;

FIG. 8 is a perspective view of the golf tool of FIGS. 1-7 but showing the divot repair element thereof fully extended;

FIG. 9 is a top plan view of the tool as shown in FIG. 8;

FIG. 10 is a bottom plan view of the tool as shown in FIG. 8;

FIG. 11 is an elevation view of the front side of the tool as shown in FIG. 8; and,

FIG. 12 is an elevation view of the back side of the tool as shown in FIG. 8.
